SMOKER'S PIPE

Elmer R. Schwinn, Chicago, Ill.

Application February 18, 1939, Serial No. 257,042

4 Claims. (Cl. 131—218)

The invention relates to smokers' pipes.

One object of the invention is to provide a pipe for this purpose which is provided with efficient means for retaining the tobacco juices and the condensate from the smoke in the stem of the pipe to prevent them from reaching the mouth of the smoker.

Another object of the invention is to provide a pipe which is sanitary and can be easily cleaned.

Another object of the invention is to provide a construction which can be produced at a low cost.

Other objects of the invention will appear from the detailed description.

In the drawing, Fig. 1 is a vertical longitudinal section of a pipe embodying the invention. Fig. 2 is a horizontal section on line 2—2 of Fig. 1. Fig. 3 is a transverse section on line 3—3 of Fig. 1. Fig. 4 is a transverse section on line 4—4 of Fig. 1. Fig. 5 is a transverse section on line 5—5 of Fig. 1. Fig. 6 is a perspective of the integral mouthpiece and core which fits in the hollow stem. Fig. 7 is a similar perspective viewed from the opposite side. Fig. 8 is a perspective of the stem.

The invention is exemplified in a pipe embodying a bowl 10 which may be formed of any suitable or usual material. An extension 11 is formed on the lower portion of the bowl which is connected by a duct 12 with the lower portion of the tobacco chamber in the bowl. A tubular stem 13 is provided with a screw-thread 15 which is threaded into the extension 11 and is removable therefrom. Stem 13 is shouldered against the end of extension 11 so that when the stem is screwed into the extension 11, the former will be secured against rotation relatively to the bowl. The stem is preferably made of non-corrosive material, such as a plastic composition or amber, to prevent corrosion and also to render the contents of the stem visible.

A mouthpiece 16 is provided with a cylindrical portion 17 which fits snugly in the outer end of sleeve 13 and is provided with a shoulder 18 adapted to abut against the end of sleeve 13 to limit the inward movement of the mouthpiece in the said stem. A core 19 integrally formed with mouthpiece 16, is adapted to fit in sleeve 13 and its inner end 20 terminates inwardly of the shoulder 18 in the sleeve and forms therewith a chamber 21a. This chamber communicates with the opening 12 in the pipe-bowl, through the bore 22 at the inner end of the stem. The core 19 is provided at its inner end

with a cylindrical inner end 23 which fits snugly in the bore of stem 13. Between cylindrical portions 23 and 17 the core is rectangular in cross-section with substantially flat sides which form four longitudinally extending chambers 24, 25, 26, and 27 between said cylindrical portions which are chordal in cross-section through which the smoke is consecutively drawn. A notch 28 extends longitudinally through cylindrical portion 23 to connect chamber 24 with the chamber 21a in the stem. A notch 29 is cut in the meeting corners of the core adjacent cylindrical portion 17 to connect side chamber 24 and bottom chamber 25. A notch 30 is cut in the core adjacent cylindrical portion 23 to connect bottom chamber 25 and side chamber 26. A notch 31 is cut in the core adjacent cylindrical portion 17 to connect side chamber 26 and top chamber 27. A draft-duct 32 extends longitudinally through the mouthpiece 16 and communicates with a vertically extending branch-duct 33 which communicates with the top chamber 27. The mouthpiece and core are made of non-corrosive and partially transparent material, such as suitable plastic or amber, for sanitary purposes. The flat faces of the core are each formed with staggered rows of pockets 35.

In operation, the smoke drawn through the mouthpiece passes from the bowl through ducts 12 and bore 22 into chamber 21a. From said chamber the smoke passes successively through notch 28 into chamber 24, thence lengthwise of chamber 24, through notch 29 into chamber 25, thence lengthwise of chamber 25 through notch 30 into chamber 26, thence lengthwise of chamber 26 through notch 31 into chamber 27, and lengthwise of chamber 27 to branch duct 33 and thence through the draft-duct 32. In traversing these chambers and ducts the tobacco juices and condensate from the smoke are retained around the core and within the stem. The condensate collects in the recesses 35. As a result, the smoke passing out through duct 32 is free from condensate and tars and cools.

The invention is not to be understood as restricted to the details set forth, since these may be modified within the scope of the appended claims, without departing from the spirit and scope of the invention.

Having thus described the invention, what I claim as new and desire to secure by Letters Patent is:

1. In a smoking device comprising a tubular stem connected to receive the smoke, a mouthpiece and a core on the mouthpiece having cylind-

- drical portions at its ends fitting in the stem and polygonal in cross-section between said cylindrical end portions, the polygonal portions having substantially flat faces with the corners 5 between them fitting in the stem to form chambers which are chordal in cross-section, the core being provided with ducts for directing the smoke longitudinally back and forth through said chambers in succession, the mouthpiece 10 having a draft-duct communicating with the chordal chamber to which the smoke last passes.
2. In a smoking device comprising a tubular stem connected to receive the smoke, a mouthpiece and a core on the mouthpiece having 15 cylindrical portions at its ends fitting in the stem and polygonal in cross-section between said cylindrical end portions, the polygonal portions having substantially flat faces with the corners 20 between them fitting in the stem to form chambers which are chordal in cross-section, the core being provided with a notch across its inner cylindrical end, and notches for directing the smoke longitudinally back and forth through said chambers in succession, the mouthpiece having 25 a draft-duct communicating with the chordal chamber to which the smoke last passes.
3. In a smoking device comprising a tubular stem connected to receive the smoke, a mouthpiece and a core on the mouthpiece having

cylindrical portions at its ends fitting in the stem and polygonal in cross-section between said cylindrical end portions, the polygonal portions having substantially flat faces with the corners 5 between them fitting in the stem to form chambers which are chordal in cross-section, the core being provided with ducts for directing the smoke longitudinally back and forth through said chambers in succession, the mouthpiece having 10 a draft-duct communicating with the chordal chamber to which the smoke last passes, and 15 recesses in the faces.

4. In a smoking device comprising a tubular stem connected to receive the smoke, a mouthpiece and a core on the mouthpiece having 15 cylindrical portions at its ends fitting in the stem and polygonal in cross-section between said cylindrical end portions, the polygonal portions having flat faces with the corners between them 20 fitting in the stem to form chambers which are 25 chordal in cross-section, the core being provided with ducts for directing the smoke longitudinally through said chambers in succession, the mouthpiece having a draft-duct extending through the core and communicating with the chordal chamber to which the smoke last passes adjacent the inner cylindrical end.
